UNITED STATES PATENT OFFICE.

HENRY W. PETERS, OF BOSTON, MASSACHUSETTS.

DESIGN FOR A BADGE, PIN, RING, EMBLEM, OR ARTICLE OF SIMILAR NATURE.

Application filed April 25, 1922. Serial No. 1,963. Term of patent 7 years.

To all whom it may concern:

Be it known that I, HENRY W. PETERS, a citizen of the United States, residing at Boston, in the county of Suffolk and State of Massachusetts, have invented a new, original, and ornamental Design for Badges, Pins, Rings, Emblems, or Articles of Similar Nature, of which the following is a specification, reference being had to the accompanying drawing, forming part thereof.

I claim:

The ornamental design for a badge, pin, ring, emblem, or article of similar nature, as shown.

HENRY W. PETERS.
